US00D803250S

(12) **United States Design Patent** (10) **Patent No.:** **US D803,250 S**
(45) **Date of Patent:** **** Nov. 21, 2017**

(54) **DISPLAY PANEL WITH GRAPHICAL USER INTERFACE**

H04N 21/00; H04N 21/234; H04N 21/431; H04N 21/4312; H04N 21/4314; H04N 21/4316

See application file for complete search history.

(71) Applicant: **LG ELECTRONICS INC.**, Seoul (KR)

(72) Inventors: **Kunho Lee**, Seoul (KR); **Younghoon Kim**, Seoul (KR); **Youngwook Nam**, Seoul (KR)

(73) Assignee: **LG ELECTRONICS INC.**, Seoul (KR)

(**) Term: **15 Years**

(21) Appl. No.: **29/577,923**

(22) Filed: **Sep. 16, 2016**

(30) **Foreign Application Priority Data**

Mar. 17, 2016 (KR) 30-2016-0012535

(57) **CLAIM**

The ornamental design for a display panel with graphical user interface, as shown and described.

DESCRIPTION

The FIGURE is a front view of a display panel with graphical user interface showing our new design.

The broken lines depict portions of the display panel with graphical user interface that form no part of the claimed design. The dash-dot broken lines define the bounds of the claimed design and form no part thereof.
